(57) **CLAIM**

The ornamental design for an adhesive tape dispenser, as shown and described.

DESCRIPTION

FIG. 1 is a perspective view of an adhesive tape dispenser; FIG. 2 is a right side view thereof, the left side view being a mirror image of the right side view;

FIG. 3 is a top view thereof;

FIG. 4 is a bottom view thereof;

FIG. 5 is a front view thereof; and,

FIG. 6 is a rear view thereof.

The broken lines shown on the serrated cutting element indicate unclaimed subject matter. The broken lines shown on the roll of tape, the circle in the upper right portion of FIG. 2, and the portion below the cutting blade indicate unclaimed subject matter. All other broken lines indicated soft contours of the dispenser.
